X-RAY TUBE

Zed J. Atlee, Elmhurst, Ill., assignor to General Electric X-Ray Corporation, Chicago, Ill., a corporation of New York

Application June 15, 1942, Serial No. 447,030

12 Claims. (Cl. 250—145)

The present invention relates in general to electronics and has more particular reference to X-ray generators.

An important object of the invention is to provide an improved cathode structure protected against the deleterious effects resulting from electronic bombardment.

Another important object is to provide a cathode structure having portions thereof formed of material highly resistant to disintegration under electronic bombardment; a further object being to locate such portions in the cathode structure at a zone or zones exposed to electronic bombardment.

Another important object is to provide a cathode structure having inserts of molybdenum, tungsten or other suitable material highly resistant to disintegration when subjected to electronic bombardment, such inserts being placed in the cathode structure at the surfaces thereof which are apt to be subjected to electronic bombardment.

Another important object is to provide a cathode structure particularly for use in X-ray generators having an anode adapted to receive, within the area of a focal spot therein, impingement of electrons emitted by the cathode, wherein, when operated at high electrical pressure, the anode may become overloaded and itself reach an electron emitting temperature at the focal spot, thereby constituting the anode as an electron emitting source capable of projecting electrons from the focal spot upon facing portions of the cathode structure, the cathode being reinforced at its said facing portions to resist disintegration or other deleterious effects of bombardment by electrons emitted by the anode; a further object being to eliminate cathode filament failure due to increased emission thereof caused by destructive effects of electronic bombardment of the cathode structure in the vicinity of the filament; a still further object being to minimize metallic deposit on the filament and on the envelope of the generator due to melting of the cathode structure under bombardment, and the resulting failure of the envelope due to such metallic deposits.

These and numerous other important objects, advantages, and inherent functions of the invention will be fully understood from the following description, which, taken in connection with the accompanying drawing, discloses a preferred embodiment of the invention.

Referring to the drawing:

Figure 1 is a sectional view taken through an X-ray tube embodying the present invention;

Figure 2 is an enlarged sectional view taken through the anode and cathode comprising parts 5 of the tube shown in Figure 1;

Figure 3 is an end view of the cathode shown in Figure 2; and

Figure 4 is a sectional view taken substantially along the line 4—4 in Figure 3.

10 To illustrate the invention, the drawing shows an X-ray generator or tube 11 comprising spaced anode and cathode electrodes 13 and 15, sealed in an enclosing, preferably glass, envelope 17.

The anode 13 may be of any suitable or preferred construction and is suitably mounted in the envelope 17 and sealed therein at one end of the envelope by a glass-to-metal seal 19 through which a portion 20 of the anode extends outwardly of the envelope to provide for cooling the anode.

15 The cathode 13 likewise is sealed in the envelope, preferably by a glass-to-metal seal 21 at the end of the envelope remote from the seal 19, said cathode being connected within the envelope to conductors 23 extending outwardly of the envelope through the seal 21 for the purpose of energizing the cathode from a suitable source of cathode energizing current outwardly of the envelope. The anode and cathode are supported in coaxial spaced apart alignment in the envelope and have facing heads.

20 It should be understood that X-ray generators function to produce X-rays in response to the activation of the anode as an X-ray source by impingement on the head of the anode of electrons emitted by and from the cathode. The cathode head facing the anode is formed with a cavity or cup 25 in which is disposed an electron emitting filament 27. The filament 27 is connected with the conductors 23 and may be constituted as an electron emitting element when energized by the passage therethrough of current supplied through the conductors 23. By applying an electrical potential between the filament 27

25 and the facing head of the anode, as by connecting one of the conductors 23 and the outwardly extending portions 20 of the anode with a suitable source of electrical potential, electrons emitted by the filament 27 may be caused to travel from the filament as an electron stream 29 and impinge upon a portion of the head of the anode forming a target area 31. The cup 25 serves to focus the electrons comprising the stream 29 upon the target zone 31.

30 35 40 45 50 55 It will be noted that the head of the anode

may be inclined with respect to the direction of the electron beam 29 in order that X-rays generated at the target area 31 may be transmitted thence as an X-ray beam 33 directed outwardly of the envelope through a portion of the lateral walls thereof, said portion preferably being of reduced thickness opposite the head of the anode, thereby forming an X-ray window 35 in the envelope. During the operation of the X-ray generator a considerable amount of heat is developed in the anode which may be dissipated outwardly of the envelope by radiation from the anode through the envelope walls and by conduction through the anode and its outwardly extending portion 20.

If the generator, as frequently happens when operated as a self-rectified diagnostic tube, is overloaded, the focal spot 31 may, and frequently does, reach a temperature at which the focal spot itself becomes an electron emitting source of electrons which may pass thence as a secondary beam of electrons 37 focused upon a portion of the cathode structure.

The establishment of such a secondary beam of electrons impinging upon a portion of the cathode structure may result in destructive bombardment of the portions of the cathode structure upon which impinge the electrons comprising such beam. Where the cathode head comprises iron or nickel, which are the metals usually employed in making cathode heads, such electronic impingement may cause disintegration of the head by melting thereof at the place of impingement. Electronic bombardment of the cathode head tends to raise the temperature thereof and of the filament 27 mounted thereon, thereby tending to cause failure of the filament as a result of increased electron emission therefrom. Melting of the cathode head metal under secondary bombardment of the character described results in the sputtering of the melted material upon the electrodes and upon the surrounding walls of the envelope. Excessive metallic deposits on the envelope may cause the same to fail, while metallic deposit upon the electrodes tends to impair the operating efficiency thereof, and to cause filament failure.

In order to overcome the deleterious effects of electron bombardment of the cathode head, the head is reinforced and protected at the portions thereof which are apt to be subjected to electronic bombardment. This is accomplished by applying to said portions an insert 39 comprising material such as molybdenum or tungsten having the ability to resist melting under electronic bombardment. The insert 39, as shown more particularly in Figures 3 and 4, comprises a plug of material set into the face of the cathode head at the zone thereof which faces the anode focal spot 31, the plug, in the illustrated embodiment, being disposed in the head in position lying in the path of such electrons as may emanate at right angles from the anode focal spot 31. The plug extends in the cathode cup 25 at one end thereof, said cup, in the embodiment shown, being of elongated configuration to receive the elongated filament 27. The plug may be secured to the head and integrated therewith as by brazing or by any other suitable joining process, to form an electron receiving shield on the cathode head to protect the same against destructive effects of electron bombardment.

It is thought that the invention and its numerous attendant advantages will be fully understood from the foregoing description, and it is

obvious that numerous changes may be made in the form, construction and arrangement of the several parts without departing from the spirit or scope of the invention, or sacrificing any of its attendant advantages, the form herein disclosed being a preferred embodiment for the purpose of illustrating the invention.

The invention is hereby claimed as follows:

1. In a device of the class described, an anode and a cooperating cathode comprising a head and an electron emitting source carried on said head in position to emit electrons for impingement upon said anode at a target zone therein, said cathode head having inserted portions comprising material characterized by a high melting temperature and resistance to disintegration under electronic bombardment when heated to high temperature, said portions being disposed in position to receive impingement of electrons emitted by said anode.

2. In a device of the class described, an anode and a cooperating cathode comprising a head and an electron emitting source carried on said head in position to emit electrons for impingement upon said anode at a target zone therein, said cathode head having inserted portions comprising tungsten and characterized by resistance to disintegration under electronic bombardment at high temperature, said portion being disposed in position to receive impingement of electrons emitted by said anode.

3. In a device of the class described, an anode and a cooperating cathode comprising a head and an electron emitting source carried on said head in position to emit electrons for impingement upon said anode at a target zone therein, said cathode head having inserted portions comprising molybdenum and characterized by resistance to disintegration under electronic bombardment at high temperature, said portion being disposed in position to receive impingement of electrons emitted by said anode.

4. In a device of the class described, an anode and a cooperating cathode comprising a head and an electron emitting source carried on said head in position to emit electrons for impingement upon said anode at a target zone therein, said cathode head comprising metal such as iron or nickel and having inserts of material having a melting temperature higher than that of iron or nickel and characterized by resistance to disintegration under electronic bombardment at high temperature, said inserts being disposed in position to receive impingement of electrons emitted by said anode.

5. In a device of the class described, an anode and a cooperating cathode comprising a head and an electron emitting source carried on said head in position to emit electrons for impingement upon said anode at a target zone therein, said cathode head comprising metal such as iron or nickel and having inserts of tungsten characterized by resistance to disintegration under electronic bombardment at high temperature and being disposed in position to receive impingement of electrons emitted by said anode.

6. In a device of the class described, an anode and a cooperating cathode comprising a head and an electron emitting source carried on said head in position to emit electrons for impingement upon said anode at a target zone therein, said cathode head comprising metal such as iron or nickel and having inserts of molybdenum characterized by resistance to disintegration un-

der electronic bombardment at high temperature and being disposed in position to receive impingement of electrons emitted by said anode.

7. A cathode comprising a head of material subject to disintegration when electronically bombarded and an insert of material highly resistant to disintegration under electron bombardment carried on said head in position to intercept electrons emitted from a predetermined source whereby to protect the head against disintegration by electronic bombardment from said source.

8. A cathode comprising a head of material subject to disintegration when electronically bombarded and an insert of tungsten carried on said head in position to intercept electrons emitted from a predetermined source whereby to protect the head against disintegration by electronic bombardment from said source.

9. A cathode comprising a head of material subject to disintegration when electronically bombarded and an insert of molybdenum carried on said head in position to intercept electrons emitted from a predetermined source whereby to protect the head against disintegration by electronic bombardment from said source.

10. A cathode comprising a head of material readily fusible under electronic bombardment and an insert on said head at an area thereof subject to bombardment, said insert comprising material having a high melting temperature and adapted to receive electrons emitted from a predetermined source and protect said head against disintegration by electrons emitted from said source.

11. A cathode comprising a head of material readily fusible under electronic bombardment and an insert on said head at an area thereof subject to bombardment, said insert comprising tungsten adapted to receive electrons emitted from a predetermined source and protect said head against disintegration by electrons emitted from said source.

12. A cathode comprising a head of material readily fusible under electronic bombardment and an insert on said head at an area thereof subject to bombardment, said insert comprising molybdenum adapted to receive electrons emitted from a predetermined source and protect said head against disintegration by electrons emitted from said source.
